CHILD'S CAR SEAT

Gerard K. Leistikow, Hermosa Beach, Calif., and Raymond A. Lo Turco, Columbus, Ind., assignors to Hamilton Cosco, Inc., Columbus, Ind.

Filed June 16, 1969, Ser. No. 17,732

Term of patent 7 years

Int. Cl. D6—01

U.S. Cl. D6—7

Fig. 1

Fig. 2

Fig. 3

Fig. 4

FIG. 1 is a front elevation of a child's car seat showing our new design;

FIG. 2 is a side elevation thereof;

FIG. 3 is a top plan view thereof, and

FIG. 4 is a rear elevation thereof.

The design is characterized by the unitized tubular base support as best illustrated in FIGS. 1, 2 and 4.

We claim:

The ornamental design for a child's car seat, as shown and described.
